UNITED STATES PATENT OFFICE

HOMER G. KELLOGG, OF DETROIT, MICHIGAN, ASSIGNOR TO MOTOR PRODUCTS CORPORATION, OF DETROIT, MICHIGAN, A CORPORATION OF NEW YORK

METAL-WORKING MACHINE

Application filed August 9, 1926. Serial No. 128,249.

This invention relates to metal working machines and more especially to means for imparting a predetermined longitudinal contour to the molding or other strips operated upon and further to means for automatically starting and stopping the apparatus, at the completion of each operation.

The invention relates more especially to machines of this general character in which strips of predetermined length are adapted to be operated upon and which are designed to have imparted thereto a predetermined longitudinal contour and to coordinate the several operations of the apparatus this invention contemplates means operated by the strip for controlling the starting and stopping of the apparatus.

The several objects, advantages and novel details of construction of this invention will be made more apparent as this description proceeds, especially when considered in connection with the accompanying drawings wherein;

Figure 1 is a fragmentary side elevational view of a machine constructed in accordance with this invention.

Figure 2 is an end elevational view of the structure shown in Figure 1 as seen from the left.

Figure 3 is an enlarged fragmentary view showing certain details of construction and

Figure 4 is a fragmentary plan view.

Referring now particularly to the drawings wherein like reference characters indicate like parts, it will be noted that the machine includes a frame 10 upon which are mounted a plurality of driven guiding or forming rolls or both 11 whereby the strip being operated on is advanced through the machine toward the left as viewed in Figure 1 whereupon a strip of the desired cross sectional configuration may be evolved from a flat strip if a plurality of forming rolls are employed or a strip preformed to the desired cross sectional configuration guidingly advanced through the machine. It will be obvious as this description proceeds that the invention is applicable with equal facility and corresponding utility to machines where- in a strip of predetermined cross section is

guidingly advanced or wherein a strip is first formed to a predetermined cross sectional area and then bent to the desired longitudinal contour.

Arranged adjacent the end of the table or bed 10 of the machine is a pair of rolls 12 and 13, the roll 13 being mounted about a fixed axis 14 while the roll 12 is rotatable about the axis 15 the bearings of which are formed in blocks 16 carried upon frames 17. Obviously a frame 17 is arranged at each end and these frames are oscillatably mounted on the axis 14 of the lower roll 13. The upper roll 12 is adapted to be rocked or oscillated about the pivot or axis 14 for imparting to the strip S the predetermined longitudinal contour.

For rocking the frame member 17 and consequently the roll 12 I provide a mechanism which includes a rod or extension 18 projecting forwardly from the frame 17 and provided with a cam engaging extension 19 preferably adjustably connected thereto by means of a bracket 20. The lower end 21 of the extension 19 is adapted to engage the peripheral face of a cam 22 loosely mounted upon a shaft 23. The shaft 23 is normally constantly rotating, being driven from a source of power (not shown). Keyed to the shaft 23 for rotation therewith is a ratchet or clutch wheel 24 with which a laterally movable clutch member 25 is adapted to engage. A spring 26 normally urges the clutch member 25 into engagement with the clutch wheel 24 but the action of this spring is opposed by a bell crank lever 27 pivotally secured to the cam 22 as at 28, one arm of which is adapted for engagement under a pin 29 extending laterally from the clutch member 25. The other arm of this clutch control lever is engageable with a lateral extension 30 of a lever 31 pivotally mounted as at 32 to the bed of the machine. This lever is provided with an upwardly and laterally projecting extension 33 provided with an inclined target plate 34 adapted to be positioned in the path of travel of the strip S and to be engaged thereby for operating the clutch.

The operation of the mechanism just de-

scribed is as follows: As the strip is advanced through the machine its forward end engages the target 34 as suggested in Figure 4 and owing to the inclination thereof rocks 5 lever 31 about its pivot 32 in a lateral or transverse direction so as to disengage the lateral or hook-shaped end 30 from behind the arm 36 of bell crank lever 27. This permits spring 26 to force the clutch member 10 25 downwardly whereby it engages clutch wheel 24, which is constantly rotating together with shaft 23, thereby locking cam wheel 22 to the shaft 23 for rotation therewith. Thus the cam 22 is rotated, the lever 15 31 being held in this inoperative position by reason of the engagement of the strip S with the target 34. However, a spring 35 having its end secured respectively to the end of the lever 31 and the bed of the 20 machine 10 tends to rock this lever back to its normal position wherein the laterally extending end 30 is in the path of the arm 36 of the bell crank lever 27. Thus when the strip S has passed beyond the target 34 25 spring 35 will return the lever 31 to its normal position so as to position the end 30 of this lever in the path of arm 36 of bell crank lever 27 when this cam control lever has been brought again substantially in the 30 position illustrated in Figure 3 by reason of the rotation of the cam 22. Hence the arm 36 of the lever 27 will be engaged by the end 30 of the lever 31 and rocked about its pivot 28 to raise the clutch member 25 from 35 engagement with clutch wheel 24 to thus stop the rotation of cam 22. Therefore, the mechanism operates to start the rotation of cam 22 as the strip S starts between the pair of rolls 12-13 and to interrupt or stop the 40 rotation of this cam as the end of the strip passes from between these rolls. Thus the period of operation of this part of the machine is dependent upon the length of the strip being operated upon and in the embodiment of the invention herein shown this period is sufficient to permit one complete rotation of the cam 22. Obviously however, the length of the period of operation may be such as to only permit of a partial rotation of the cam 22 or of several complete rotations thereof as the character of the job being performed dictates.

The peripheral configuration of the cam 22 is so selected that it will impart to the 55 frames 17 and consequently to the upper roll 12 a rocking movement about the lower fixed roller 13 so as to bend the strip S to the desired longitudinal contour which in 60 the present embodiment of the invention involves a shape substantially as suggested in dotted lines in Figure 1. As will be noted the strip S has been bent into two reverse curves and for this purpose the upper roller 65 12 is first rocked to the left as seen in Fig-

ures 1 and 3 and then to the right of a line passing vertically through the axes 14 and 15 of these rollers in the position as shown in Figure 1. However, it will be immediately apparent that the peripheral contour 70 of the cam 22 will be designed to oscillate the roll 12 as is necessary to impart to the workpiece the desired longitudinal contour, it being obvious that where the periphery of the cam is concentric with the axis of the rotation that dwell portions will be provided to produce straight or non-curved portions in the workpiece S.

While the structural details of the embodiment of the invention herein shown and described are found to give particularly good results in practice nevertheless it will be immediately obvious to those skilled in this art that various changes may be made in many of the essential and all of the non-essential details of the invention as may be found necessary or expedient and to this end reservation is made to make such changes as may come within the purview of the accompanying claims.

What I claim as my invention is:

1. The combination with means for advancing a molding strip or the like, of a pair of rolls engaging opposite sides of said strip and means for oscillating one of said rolls about the axis of the other roll to bend said strip to a predetermined longitudinal contour.
2. The combination with means for advancing and for fashioning to a predetermined longitudinal contour a molding strip or the like, of means for actuating said fashioning means and means operated by said strip and mechanically connected to said actuating means for controlling the same to control the said fashioning means.
3. The combination with means for advancing a molding strip, of a pair of rolls engaging said strip, means for oscillating one of said rolls for fashioning said strip longitudinally and means controlled by said strip for controlling said roll oscillating means.
4. In a machine of the character described, the combination with means for longitudinally fashioning a molding strip or the like, of a cam for actuating said fashioning means, a clutch member carried by said cam for actuating the same and means operated by said strip and connected to said clutch for operating the same to control the operation of said cam.
5. In a machine of the character described, means for advancing a strip and for longitudinally fashioning said strip, including a pair of rolls engaging said strip and means for oscillating one of said rolls with reference to the other while maintaining its engagement with the said strip to bend said

- strip to the said predetermined longitudinal contour.
6. In a machine of the character described, a pair of rolls arranged for engagement with opposite surfaces of a strip to be fashioned, means for mounting one of said rolls for oscillation about the other and cam control means for oscillating said roll.
7. In a machine of the character described, a pair of rolls, means for oscillatably mounting one of said rolls, cam means for oscillating said roll and means controlled by the strip being operated upon for causing an operation of said cam.
- 15 8. The combination of means for advancing a molding strip or the like, of means for fashioning said strip longitudinally, cam means for operating said fashioning means, a clutch for controlling said cam and means for controlling said cam by the strip being operated upon.
9. In a machine of the character described, constantly driven means for advancing a molding strip or the like, normally inactive means for longitudinally fashioning said strip and means controlled by the strip for operating said fashioning means.
10. In a machine of the character described, means for advancing a molding strip or the like, means for longitudinally fashioning said strip, cam means for operating said fashioning means, a constantly operated driving means for said cam, a clutch for coupling said cam to said driving means and means controlled by the strip being operated upon for controlling said clutch.
11. In a machine of the character described, the combination with a roll movable in opposite directions to bend a strip in reverse directions, of means including a cam periodically actuated by said strip for controlling the direction of movement of said roll.
- 45 12. In a machine of the character described, the combination with means operable to bend a strip in reverse directions, of a normally inactive cam for controlling said bending means and means actuated by the said strip for controlling the operation of said cam.
13. In a machine of the character described, the combination with means for advancing a molding strip through the machine, of a roll movable to bend the said strip in reverse directions, and means operated by the strip during advancement of the latter for moving the said roll through a predetermined path to control the bending of the said strip.
14. In a machine of the character described, the combination with means for advancing a molding strip through the machine, of a roll movable to bend the strip in reverse directions, and means controlled by the said strip for moving the said roll.
15. The combination with means for advancing a molding strip or the like and means for longitudinally fashioning said strip, of a cam for actuating said fashioning means to change the longitudinal contour of the strip, a clutch for controlling the operation of said cam, and means operated by said strip and connected to the clutch for actuating the latter.
- 70 16. In a machine of the character described, the combination with means for fashioning a molding strip or the like, of a cam for actuating said fashioning means, a clutch associated with said cam, and means operated by said strip and connected to said clutch for actuating the latter to control the operation of said cam.
- 75 17. In a machine of the class described, the combination with means for advancing and fashioning a molding strip, of a cam for actuating said fashioning means, a clutch for controlling the operation of said cam, and means for actuating said clutch including a member connected to the latter and arranged in the path of travel of said strip and operated thereby.
- 80 18. The combination of means for advancing and fashioning a molding strip or the like, and means operable by said strip for automatically actuating said fashioning means to change the contour of said strip.
- 90 19. In a machine of the character described, a pair of rolls, means for oscillatably mounting one of said rolls, a drive shaft, means including a cam freely rotatably mounted upon the drive shaft for oscillating said roll and means for periodically connecting said cam to the drive shaft.
- 100 20. The combination of means for advancing and fashioning a molding strip or the like, and means arranged in the path of travel of the strip and operable by engagement with the latter to automatically adjust the fashioning means to change the contour of said strip.
- 105 In testimony whereof I affix my signature.
